CLAIM

The ornamental design for an automobile, as shown and described.

DESCRIPTION

FIG. 1 is a perspective view from the front and left of an automobile showing my new design;

FIG. 2 is a left side elevational view thereof;

FIG. 3 is a top plan view thereof;

FIG. 4 is a front elevational view thereof;

FIG. 5 is a rear elevational view thereof.

The bottom is plain and unornamented. The right side is a mirror image of the left side.
